UNITED STATES PATENT OFFICE.

ARTHUR B. SMITH, OF EDEN, NEW YORK.

NAILING-STRIP FOR CONCRETE FENCE-POSTS.

1,270,452.

Specification of Letters Patent. Patented June 25, 1918.

Application filed July 27, 1916. Serial No. 111,697.

To all whom it may concern:

Be it known that I, ARTHUR B. SMITH, a citizen of the United States, residing at Eden, in the county of Erie and State of New York, have invented certain new and useful Improvements in Nailing-Strips for Concrete Fence-Posts, of which the following is a specification.

This invention relates to a nailing strip 10 for concrete fence posts and more particularly to a strip of material which is adapted to be embedded in one side of a concrete fence post for holding the staples securely to the post whereby the strands of wire constituting the fence will be securely held in engagement with the fence post.

A further object of the invention is the provision of a nailing strip of this character which will be constructed so that the ordinary wire fastening staples, commonly used in constructing fences, can be employed for use with concrete fence posts.

A further object of this invention is the provision of a nailing strip for concrete fence posts which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a front elevation of a fence post showing the invention applied thereto.

Fig. 2 is a horizontal section.

Fig. 3 is an enlarged fragmentary vertical section on the line 3—3 of Fig. 2.

An ordinary concrete post 1 is provided on one of its faces with a dovetail groove 2 which extends longitudinally of the post for the entire length thereof. The nailing plate 3 is formed from a strip of metal and is bent to fit within the groove 2 thereby providing a channel 4 the side walls of which contact with the inner side walls of the groove 2. The longitudinal edges 5 of the side walls 6 are slightly embedded in the concrete beyond the inner wall of the groove 2. A central longitudinally extending ridge 6 is formed by bending the central portion of the plate inwardly, as clearly shown by Fig. 2 of the drawing, thereby providing the exterior groove 7. A plurality of apertures 8

are formed in the ridge 6 and are spaced apart for securing a various number of wire strands to constitute the fence.

The inner wall 9 of the groove 2 receives 60 a clench plate 10 which is adapted to receive the ends of the staples 11 when they are driven through the holes 8 so that the ends of the staples bend to force the legs of the staples outwardly at a greater angle than 65 their original angle so that when the staple is drawn into place the same will be prevented from becoming loosened. It will be noticed that a binding action occurs at the point at which the legs of the staple pass 70 through the openings 8 and, of course, the farther the staple is driven the tighter the same will bind in the openings 8 thereby effectively preventing the displacement of the staple. The strands of wire, over which the 75 staples are placed when they are driven into the nailing strip, will, as shown by Fig. 2 of the drawing, be bent slightly inwardly at a point at which they contact with the staples so that they are drawn within the 80 groove 7 thereby preventing the wires from slipping lengthwise through the staples.

From the foregoing it will be observed that a very simple and durable nailing strip for concrete fence posts has been provided, 85 the details of which embody the preferred form. I desire it to be understood however, that slight changes in the minor details of construction may be made without departing from the spirit of the invention or the 90 scope of the claims hereunto appended.

I claim:

1. A nailing strip comprising a plate bent to provide a longitudinal channel having its side walls disposed at an angle, a longitudinally extending ridge formed in the central portion of the channel formed by bending the said plate inwardly to provide an exterior groove, a plurality of fastening elements adapted to be secured to the said 100 ridge, the said ridge being provided with a plurality of apertures for receiving said fastening elements, and a clench plate extending across the said channel and adapted to receive the ends of the said fastening elements when the same are driven through the 105 said apertures.

2. A nailing strip for concrete fence posts, the latter having a dove tail groove in one of its faces, a longitudinal strip of metal bent to fit within the groove, the longitudinal edges of the said strip being embedded 110

in the concrete post beyond the bottom of the said groove, the central longitudinal portion of the said strip being bent inwardly to form a ridge extending into the said 5 groove at the center thereof, the said ridge having a plurality of apertures formed therein, and staples adapted for reception in the said apertures.

3. A nailing strip for concrete fence posts, 10 comprising a strip of metal bent to form a longitudinal channel having its side walls flared outwardly, the said fence post being provided with a longitudinal dove tail groove receiving the said strip and having 15 the flared walls in contact with the walls of the groove, the longitudinal edges of the said side walls being embedded in the con-

crete beyond the bottom of the said groove, a central longitudinal ridge formed on the 20 said plate and extending inwardly of the said groove, a clench plate mounted in the groove and in contact with the bottom wall thereof, the said side walls of the channel being engaged by the marginal edges of the 25 said clench plate, and staples extended through the said ridge and engaging with the said clench plate.

In testimony whereof I affix my signature in presence of two witnesses.

ARTHUR B. SMITH.
